UNITED STATES PATENT OFFICE

2,006,577

COMPRESSED AIR GUN

Wilfrid Perreault, Oakland, Calif.

Application April 13, 1929, Serial No. 354,835

1 Claim. (Cl. 124—8)

This invention especially relates to a compressed air toy gun and has for its primary object the providing of a novelty of the character described that will be useful for playing games and 5 for other various forms of amusement.

It is one of the objects of the invention to provide a gun of the character described that will be operative by applying a mallet against 10 resilient means that is mounted on one end of the gun barrel to compress air within the gun barrel.

It is another object of the invention to provide the compressed air means without the use of 15 valves and packing and other air leaking elements.

It is a further object of the invention to provide a gun of the character described with improved adjusting means that will permit the gun barrel to be adjusted both horizontally and 20 vertically and locked in any suitable position.

It is a still further object of the invention to provide an improved type of projectile that is 25 constructed into such a size and shape and mounted on the end of the gun barrel in such a manner that will enable the compressed air that is forced through the gun barrel to be exerted against a surface on the inner end of the projectile that has an area that is larger than the opening in the gun barrel so that a large 30 amount of the compressed air pressure will be exerted directly against the inner end of the projectile to increase the shooting distance.

The invention further consists in the particular combination, construction and association of 35 the different elements, such as described in the following specification, and possesses various other objects and features of advantage, some of which, with the foregoing, will be made manifest in the preferred form of the invention that 40 is illustrated in the drawing accompanying and forming part of the specification.

It is to be understood that it is not intended 45 to limit the invention to the embodiment shown by said drawing and description, as variations may be adapted within the scope of the invention as set forth in the claim.

In the accompanying drawing:

Figure 1 is a central longitudinal sectional view 50 of one type of entire gun assembly involving the invention.

Figure 2 is a side elevational view of a striking mallet used in the invention.

Figure 3 is a perspective view of one type of 55 gun involving the invention.

Figure 4 is a perspective view of one type of target used with the invention.

Figure 5 is a top perspective view of a plate that is fastened on the bottom of the gun barrel.

Figure 6 is a perspective view of the same plate as shown in Figure 5, the said plate being turned with its bottom facing upwards.

Figure 7 is a perspective view of the adjustable head upon which the gun barrel is mounted.

Referring in detail to the different parts 10 wherein like reference characters denote corresponding parts throughout the several views, the numeral 10 designates a gun barrel that may be made out of wood or any other suitable material, and is provided at the breech end thereof, with a 15 resilient covering 11 that is preferably made out of a suitable grade of rubber, the said covering being substantially held on the gun barrel by any suitable means, the present illustration showing an expansion or snap ring 12 depressing the covering into a circumferential groove provided in and around the outer periphery of the gun barrel. The said ring is preferably made split and is held together by means of a bolt and nut as illustrated. The ring 12 is preferably formed in a 20 manner as to provide a sight 12a that is arranged in line with a front sight 13 that is fastened on the breech end of the gun barrel. The breech end of the barrel 10 is provided with a funnel shaped opening 10a, the small end of 25 which terminates in a straight hole 10b that continues toward the muzzle end and through the gun barrel.

A plate 14, provided with a downward projection 14a, is fastened to the outer bottom surface 35 of the gun barrel by means of metal straps 15 that are preferably riveted to the plate and are provided with holes 15a so that nails or screws may be applied therethrough and into the barrel. The plate 14 is provided with a curved slot 14b, 40 to allow for circumferential movement on its tripod head, the construction of which will hereinafter be described. As hereinbefore stated, one of the objects of the present invention is to provide improved means for horizontally and vertically adjusting the range of the gun barrel. Figure 6 shows an improved means for supporting the gun and consists in providing an upper plate 16 and a lower plate 17 and hinging the two plates together in a manner that will permit one plate to be vertically swung with respect to the other. The plate 14, upon which the gun is fastened, is mounted on the top face of the plate 16 and the projection 14a is inserted in the hole 16a in said hinged plate 16 as shown 50 55

in Figure 1. A plurality of legs 25 are provided and hinged to the plate 17, thus forming a tripod for holding the gun. The numeral 26 designates a staple for holding the legs in the ground.

5 The gun is then held in the desired horizontal position by means of a threaded bolt 18 that is fixed on the plate 16 and extends through the curved slot 14b of the gun plate 14 and is provided with a standard threaded nut or handle 18a for rigidly locking the gun plate in position. It 10 will be observed that the slot 14b in the gun plate will permit the gun to be moved on a horizontal plane so that the gun may quickly be adjusted to different horizontal positions. The 15 head plate 16 is provided with a tongue 16b that extends downwardly through a slot 17a and adjacent a lug 17b that is provided on the bottom head plate 17. A standard threaded stud 19 is fixed into the said lug 17b and horizontally extends through an arc shaped groove 16c provided in said tongue. A handle 20 that is threaded to engage with the stud 19 is threaded on said stud and is constructed to tightly hold the tongue 16b against the lug 17b, and thereby permit the 20 plate 16, upon which the gun plate rests, to be vertically adjusted, thus providing simple means for adjusting the gun on a vertical plane.

25

In Figure 1 there is shown mounted in the muzzle end of the gun barrel, a projectile that is 30 preferably constructed in the form as illustrated and consists of a cone shaped cap 21 that is preferably made out of such material as rubber or leather and is fixed on the end of an oblong member 22 as illustrated. The said oblong member 22 is preferably constructed out of wooden material and is provided with a smaller diameter 35 than the hole provided through the gun barrel so that the compressed air will be exerted, not only against the inner end of the oblong member 22, but will pass into and be exerted against the 40 complete inside area of the cone shaped cap 21. Figure 2 shows a mallet 23 that is made into a form to approximately fit the funnel shaped opening 10a at the breech of the gun barrel. The 45 target shown in Figure 4 illustrates one type of target that may be used, and shows a plurality of score pockets, each of which may designate a different score numeral for making up a complete

tally. The dotted line extending from the gun in Figure 3 to the target in Figure 4 designates a line of travel of the projectile from the gun to the target. The numeral 11a provided on the resilient covering at the breech of the gun designates a striking target for the mallet. It is to be definitely understood that the resilient covering will be made of such rubber material or other resilient material that will resiliently move into and take the shape of the funnel shaped cavity 10a when the mallet is driven against the target 11a on said covering.

5 It will be noted that when the mallet is driven against said resilient covering and the covering moves into the funnel shaped cavity, air from 15 within the cavity will be immediately forced into the small hole 10b and against the projectile and shoot the projectile outwardly. From the foregoing it will be observed that this novel invention will give pleasant and interesting amusement and can be utilized into playing many different kinds of games.

10 Having thus illustrated and described a certain form of construction and arrangement of parts pertaining to the invention, it is desired to include in this application for Letters Patent of the United States of America any and all patentable novelty that exists in the invention disclosed and all that comes within the range of the invention as set forth in the claim hereinafter 15 mentioned.

20 What is claimed:

A device of the character described, having in combination a tripod, a plate mounted vertically adjustable thereon, a gun barrel mounted horizontally adjustable on said plate, an inwardly tapering opening in the breech end of the barrel, a resilient covering over said opening, a projectile constructed to be mounted in the muzzle end of the barrel, said projectile having a cone shaped 25 flexible cap provided on the front end thereof that is constructed to fit against the muzzle end of the barrel, and a mallet tapered to fit into the 30 tapered opening in the breech end of the barrel so that the projectile may be driven out of the 35 barrel substantially as described.

40 WILFRID PERREAULT.
